UNITED STATES PATENT OFFICE.

JOHN MURRAY, OF FORT WAYNE, INDIANA.

DEVICE FOR WORKING UPRIGHT FOLDING BEDS.

SPECIFICATION forming part of Letters Patent No. 375,183, dated December 20, 1887.

Application filed January 12, 1887. Serial No. 224,151. (No model.)

To all whom it may concern:

Be it known that I, JOHN MURRAY, of Fort Wayne, in the county of Allen, State of Indiana, have invented a new and useful Device 5 for the Working of Upright Folding Beds; and I do hereby declare that the following is a full, clear, and exact description of the construction and operation of the same, reference being had to the accompanying drawings as making a 10 part of this specification, in which—

Figure 1 is a rear perspective view of one corner of a folding bedstead at the head end embodying my improvements. Fig. 2 is a side elevation of the same with lowered side 15 rail shown in dotted lines. Fig. 3 is a front elevation with side rail raised. Fig. 4 is a perspective view of my improved guiding and balancing devices for the side rail. Fig. 5 is a modification of the same.

20 The object of my invention is to provide a simple, cheap, and improved means of balancing and guiding the side rails of upright folding bedsteads; and to this end the invention consists in the construction and combination 25 of devices hereinafter described and claimed.

Referring to the drawings, the letter *b* designates one of the stationary uprights forming part of the sides of the bed-casing, and *a* and *c* are cross-pieces for connecting the two uprights. 30

To the inner side of each upright *b* is firmly secured a bearing-block, *e*, having a rearwardly-inclined upper surface, as shown in Figs. 1 and 2.

35 In the inner side of the bearing-block *e*, between it and the upright *b*, is formed a diagonal groove or guideway, *d*, which receives a slide or guide-bar, *A*, pivotally connected to a

rocker, *D*, that is secured to the rear end of the side rail, *C*, as shown. 40

The rocker *D* rests on the upper inclined surface of the bearing-block *e*, and is adapted to turn or rock thereon in such a manner as to change the pivotal point of the side rail nearer its center when the bed is in a horizontal position or approaching the same, while the slide or guide-bar *A* moves upward in the groove *d*, thus guiding and holding the bed and enabling it to be balanced with greater ease than usual. 45

The guide-bar *A* and rocker *D* may be connected by a pivot-bolt, *f*, if desired, in which case it is preferable to cut away one side of the rocker to receive the upper end of the guide-bar, as shown in Figs. 1, 3, and 4; or, instead of the pivot *f*, the bar *A* and rocker *D* may 55 have a hinge connection, *G H*, as shown in Fig. 5.

The guide-bar or slide *A*, rocker *D*, and bearing-block *e* can be made of wood or metal, as desired; but if made of wood it is preferable 60 to face the wearing-surfaces with metal.

What I claim is—

In a folding bedstead, the combination, with the upright *b* and movable side rail, *C*, of the bearing-block *e*, secured to said upright and 65 provided with a diagonal groove, *d*, and an inclined upper surface, the rocker *D*, secured to the rear end of the side rail and resting on the inclined upper surface of the said bearing-block, and the slide or guide-bar *A*, pivotally 70 connected to the rocker and adapted to move in the groove *d*, substantially as described.

JOHN MURRAY.
